BOX

Frank McIntosh, New York, N. Y., assignor to Letheric, Incorporated, New York, N. Y., a corporation of New York

Application November 16, 1949, Serial No. 6,079

Term of patent 14 years

(Cl. D58—12.6)

To all whom it may concern:

Be it known that I, Frank McIntosh, a citizen of the United States, residing at New York, in the county of New York and State of New York, have invented a new, original, and ornamental Design for a Box, of which the following is a specification, reference being had to the accompanying drawing, forming part hereof.

In the drawing:

Fig. 1 is a front elevational view of a box showing my new design;

Fig. 2 is a top plan view;

Fig. 3 is a side elevational view, the opposite side being identical; and

Fig. 4 is a rear elevational view thereof.

The drawing is shaded to show contrasting appearance.

I claim:

The ornamental design for a box, substantially as shown and described.

FRANK MCINTOSH.
